UNITED STATES PATENT OFFICE

STEPHAN PODMAYER, OF ST. LOUIS, MISSOURI, ASSIGNOR TO STABILITY LEATHER
GOODS MFG. CO., OF ST. LOUIS, MISSOURI

DESIGN FOR A TRAVELING BAG

Application filed February 4, 1929. Serial No. 29,913. Term of patent 14 years.

To all whom it may concern:

Be it known that I, STEPHAN PODMAYER, a citizen of Czechoslovakia, and a resident of the city of St. Louis, and State of Missouri, and who have declared my invention of becoming a citizen of the United States, have invented a new, original, and ornamental Design for Traveling Bag, of which the following is a specification.

In the accompanying drawing, which forms part of this specification,

Fig. 1 is a plan view of a traveling bag embodying my invention,

Fig. 2 is a side elevational view of one side thereof,

Fig. 3 is a side elevational view of the other side thereof, and

Fig. 4 is an end view thereof.

I claim:—

The ornamental design for a traveling bag, as shown.

STEPHAN PODMAYER.
